UNITED STATES PATENT OFFICE.

PHILIP JACOB MEAHL, OF SUMMIT, NEW JERSEY.

MACHINE FOR MAKING MASTER-SHEETS.

1,156,701.

Specification of Letters Patent. Patented Oct. 12, 1915.

Application filed July 21, 1914. Serial No. 852,133.

To all whom it may concern:

Be it known that I, PHILIP J. MEAHL, a citizen of the United States, and a resident of Summit, in the county of Union and State of New Jersey, have invented certain new and useful Improvements in Machines for Making Master-Sheets, of which the following is a specification.

This invention relates to certain new and useful improvements in machines for making master sheets from automatic record sheets produced by manual playing on key instruments.

The object of my invention is to provide a new and improved machine of this kind by means of which a perforated copy to be used as a master sheet in a perforating machine can be made from a perforated automatically made record of manual playing; in which copy or master sheet, the individual perforations or the beginnings of slots are so located in said master sheet copy that they will correctly coöperate with the mechanically or otherwise operated selectors of a duplicating perforating machine of ordinary mechanical construction, in which the paper is fed step by step and the punches operated at corresponding intervals, the punching means being controlled automatically by selectors which in turn are controlled by the master sheet, all of which is simple in construction and effective and reliable in use.

In the accompanying drawings in which like letters of reference indicate like parts in all the figures:—Figure 1 is a vertical longitudinal sectional view of my improved machine for making master sheets, parts being broken away. Figs. 2 and 3 are elevations of the two opposite sides, parts being omitted.

In making an automatic record of manual playing on a piano or organ by an artist or skilled piano player, the paper sheet on which this record is to be made is punched or marked by a series of punching devices or markers, the operation of which is controlled from the keys manipulated by the player, such automatic recording machine of any well known type or construction, being connected with a piano on which the pianist or player performs and the record marks or cuts made in this sheet correspond to the length of time that a key was held depressed, whereby a correct visual record of each key depressed and of the time that it has remained depressed is produced. Pianists

have more or less idiosyncrasies and peculiarities in touch and the like for the purpose of bringing out the expression as they may deem it necessary and their interpretation of the composition. It will be found that in such an automatically made record sheet the individual punchings or the beginnings of slots do not coincide exactly with the positions which they should have in order to permit such a record sheet to be used as a master sheet in a mechanically operated reproducing machine for making copies of the record sheet because it is necessary that the individual punchings or the beginnings of slots shall have a certain relation to the step by step movements of the reproducing machine. It is therefore necessary to correct the record thus made automatically by the pianist or player with a view of bringing the individual punchings or the beginnings of slots in the proper relation to the steps of the reproducing machine and such corrections would have to be made laboriously at great expense and loss of time by skilled persons. The person making such corrections frequently in so doing distorts the intentions of the manual player either accidentally or intentionally. Furthermore it frequently happens that in such automatically made records not enough paper is left between succeeding openings to produce the proper paper bridges, required in such a sheet, for repeat notes if the same is to be used on a mechanical player.

In my improved machine, I use the manually produced record sheet, as it leaves the recording machine and after the bridges have been corrected and I place this into a duplicating machine for perforated music sheets using this manual recorded sheet in connection with punch controlling selectors as has been customary, these selectors being controlled by this manually made master sheet in the well known manner and the punches being operated in the well known manner and I provide a sheet on which the punches so controlled produce a copy by producing punchings or slots in the copy sheet. The manually produced record sheet now used as a master sheet is shifted step by step at a certain pre-determined speed and this mechanism is preferably driven from the main shaft of the perforating machine but it may be driven in any other suitable manner or by any suitable means. This manually made record sheet, used as a

master sheet is shifted step by step at a uniform speed, let us say 1/100th of an inch for each step. Of course this is by no means a fixed dimension and is only given 5 as an example as the feed may be 1/100th of an inch or more than 1/100th of an inch. The paper sheet on which the copy is to be made by means of the punches controlled by the manually made record, now used as a 10 master sheet, is also fed at a uniform speed, step by step and the steps for feeding the copy sheet must have a certain relation to the steps of the manually made record sheet, now used as a master sheet. If the copy 15 sheet is fed in such a manner that each step for example equals 3/16ths of an inch, which is approximately the minimum dimensions of the feed step in ordinary mechanical perforating music sheet copying 20 machine, the copy sheet will remain at rest substantially during five feeding steps of 1/100th of an inch each of the manually produced record, used as a master sheet and only after five such steps of 1/100th of an 25 inch each of the manually produced record, used as a master sheet, have been made, will the copy sheet be moved one of its feeding steps, that is 3/16ths of an inch. I have assumed that the manual record used as a 30 master sheet is moved five steps for every step of the copy sheet, but this relation can be changed at will and one feeding step of the copy sheet may be made equal to any multiple of feed steps of the manual record 35 sheet, used as a master sheet, more than two; that is to say; the manually made record, used as a master sheet, must be shifted at least two steps for each step of the copy sheet but it can be shifted three steps, four, 40 five, six or more. The distance that the copy sheet is moved by each step may be greater than the distance moved by the manual record, used as a master sheet during a number of steps of the manual record, 45 used as a master sheet corresponding to one step of movement of the copy sheet or said distance may be equal, that being immaterial but in all cases more than one feed step of the manual record, used as a master sheet 50 must be provided for each step of the copy sheet so that there will be a distinct period of rest in the feed of the copy sheet. This relation of the steps of the master sheet and copy sheet is and must be so selected that 55 the copy thus made can be used on a perforating machine operating its feed and punches step by step in such a manner that the selectors of this copying machine can coöperate with the copy thus produced as 60 stated above when used as a master sheet in this second or duplicating machine. That is, the feed of the master sheet in this second or duplicating machine must be such that the transverse rows of slots or punchings in 65 the copy thus made and now used as a

master sheet must be in a transverse line on the sheet so that the selector pins can pass into said slots or openings.

The particular embodiment shown in the drawings is constructed with a main frame 1 on which all the several parts are mounted. At the center of the main frame two standards 2 are provided, one on each side, in which is mounted the main drive shaft 3 carrying suitable means for rotating it from a source of power. On this shaft is fixed a cam disk 5 having a groove into which a pin 6 passes, which extends laterally from the top of a vertically reciprocating punch operating head 7 suitably guided in the side frames of the machine. Beneath the head 7 a transverse punch guide 8 is secured in the side frames, directly above a die holding block 9 on the top of which a die plate 10 is secured. In the punch guide 8 a series of punches 11 are guided to move vertically, each punch being provided at its upper end with a button 12 which rests in a recess 13 in the punch operating head 7, so that as the head moves upward the punches are all raised. Above each button 12 a horizontal punch controlling slide 14 is mounted on edge so that it can be shifted across the head 7 horizontally and each slide is provided in its bottom edge with a notch or recess 15 into which the button 12 of the punch directly below it can pass when said notch or recess is in alignment with the punch.

In brackets 16 at one end of the main frame 1, a transverse shaft 17 is mounted on which is secured a perforated master sheet drum 18 of conventional construction, which drum is provided at its end with sprocket teeth 20 which can pass into slots cut along the edge of the master sheet, in the well known manner. This drum is driven by suitable gearing to be described hereinafter, from the main shaft 3, so that a pre-determined relation is established between the speed of rotation of the main shaft 3 and the drum 18 and for each rotation of the main shaft, the master sheet drum is relatively shifted a certain distance. A series of horizontal selector pins 22 are guided at their free ends by a guide plate 23 adjacent to and parallel with the drum 18 and the opposite end of each of these selector pins is pivotally connected with the upper end of a curved substantially L-shaped lifting lever 24 pivoted at 25 to a bar 26 having a series of vertical slots 27 in which said lifting levers 24 are severally located. Each selector pin is connected above its pivot with one end of a spring 28, the opposite end of which is secured to a bracket 29 on the bar 26, which springs serve to pull on the upper ends of the lifting levers, thereby gently pressing the free ends of the selector pins against the master sheet passing over the drum 18, the lower ends of which lifting le- 125

vers each terminate in a head 30 resting within a notch 31 of a thrust block 32 of which one is provided for each lifting lever, said thrust blocks being slidably guided in 5 slots in the bar 26 to move up and down vertically under the action of the lifting levers 24. Whenever a hole appears in the master sheet opposite the row of guide holes in the guide plate 23 the corresponding selector pin is forced to the right into said 10 hole in the master sheet under the action of a spring 28 and thereby the corresponding thrust block 32 is raised. A carriage 33, extending transversely across the machine frame is guided at its ends in horizontal 15 guides 34 so as to reciprocate horizontally and in said carriage one selector rod 35 is mounted for each slide 14 and corresponding lifting lever 24, one end of said selector rod being pivotally connected with the corresponding slide 14 and the opposite end being connected with a U-shaped piece 36 mounted slidably in the carriage in such a manner that the ends 37 of the long shanks 20 of the several pieces 36 project beyond the right hand side of the carriage and into the paths of the several thrust blocks 32 whereas the shorter shanks of the U-shaped piece are each connected with one end of a spring 25 38, the opposite end of which is attached to the carriage, which springs thus serve for keeping the ends 37 of the U-shaped piece projected beyond the right hand side of the carriage, and above the thrust blocks 32. 30 The carriage 33 is provided with a laterally projecting pin 39 which is engaged by the lower forked end of a lever 40 pivoted at 41 and connected by a link 42 with a plate 43 having a longitudinal slot 44 through 35 which the main shaft 3 passes. This plate carries a pin 45 which projects into a cam groove 46 of a cam disk 47 secured on the main shaft so that as the main shaft is rotated the lever 40 is rocked to and fro and 40 correspondingly reciprocates the carriage 33 toward and from the thrust blocks 32. Adjacent to the outer edges and upper end parts of each group of lifting levers 24, I provide a bar 50 which can swing toward 45 and from the upper parts of the lifting levers and serves as a restoring bar for bringing the lifting levers 24 and selector pins 22 connected therewith into normal position, once for each rotation of the main shaft. 50 This bar 50 is connected by arms 51 at its ends with a rock shaft 52 extending transversely across the machine, which rock shaft is operated by a bar 53 from a cam 54 of any suitable construction on the main shaft 3. 55 A shaft 55 is driven by suitable gearing of any suitable kind from the main shaft 3 and I prefer to use for this purpose the Geneva star wheel so well known in machines of this kind, that it is not necessary 60 to illustrate or describe it and from this

shaft motion is transmitted by the worm shaft 60 and worm wheel 61 or any other suitable means to the drum 18 so as to give the same a step by step movement, let us say of one hundredth of an inch per step 70 on the periphery of said drum 18.

On one end of the main shaft 3 is mounted a small pinion 62 which engages a cog wheel 63 which has a diameter five times as great as the pinion 62 on the shaft 3 so 75 that the wheel 63 will make only one revolution for every five revolutions of the main shaft. The wheel 63 carries a beveled or cam tooth 64 projecting beyond its rim and which can engage a worm wheel 65 fixed 80 on an inclined shaft 66 carrying at its lower end a beveled cog wheel 67 which engages a beveled cog wheel 68 on the shaft of a drum 69 over which the sheet 70 is passed 85 on which the copy is to be produced, said drum having cogs 71 which can pass into suitable notches in the edges of the sheet 70 so as to provide uniform speed and direction. The drum 18 is rotated a pre-determined distance or step for each rotation of 90 the main shaft. We will assume that the distance that this drum and the sheet thereon are moved for each step is 1/100th of an inch. As the cam tooth 64 only engages the worm 95 65 once for every five rotations of the main shaft 3, it follows that the sheet 70 on which the copy is to be produced remains substantially at rest during the time that the drum 18 over which the manual record, used as a master sheet, passes, is moved the distance 100 of five steps, that is to say, the sheet 70 remains at rest during practically all the time that the five reciprocations of the selector pins 22 are made. As the sheet 70 on which the perforated copy is being produced is fed uniform distances, never more and never less and such distance corresponds to the amount of paper removed by each punching, except when a single punching is made, the single punchings or beginnings 105 110 of slots are always produced in a pre-determined position. For example we will assume that the paper sheet 70 has been fed and remains at rest and while this paper is at rest the selector pins 22 move to the right but none of them enter a hole in the automatic record sheet used as a master sheet and the consequence is that for this rotation of the main shaft no die 7 is forced downward. The same thing may occur for 115 the second, third, fourth or fifth stroke of the selector pins 22. If at the fifth stroke, one or more selector pins pass through holes in the automatic record used as a master sheet, the corresponding punches will be 120 125 forced down. Of course it might happen that one or more pins pass through corresponding holes in the automatic record sheet, used as a master sheet, at the first stroke of the pins 22 to the right or at the second, 130

third, fourth or fifth, but some pins might pass through at the first stroke of the pins 22 to the right of the same pins and others might pass through at the second stroke or 5 third, or fourth, or fifth stroke but whenever such a pin passes through, a punching will be made in the copy sheet 70 but all the punchings thus made in the copy sheet 70 during these five strokes of the selector 10 pins to the right will all be produced on one and the same transverse line of the copy sheet 70 because this copy sheet 70 has been at rest during all this time. Then the copy sheet 70 is moved one step which we have 15 agreed shall be equal to $3/16$ ths of an inch and then the selector pins 22 can make five strokes at the automatic sheet used as a master sheet and so on. The result will be that the copy produced on the sheet 70 is 20 an exact copy of the perforations on the manual record sheet, although it may be on an enlarged scale but in this copy produced on the sheet 70, the individual punchings or the beginnings of slots are on straight 25 transverse lines separated from each other a distance corresponding to the stroke of the master sheet drum on a reproducing perforating machine or to a multiple of such distances. Such a copy as produced on the 30 sheet 70 can thus be used at once as a master sheet in a mechanically operated duplicating machine or manifolding machine because the transverse rows of slots of individual perforations or beginnings of slots have a 35 certain pre-determined or fixed relation to the feed of the perforating machine and to the movements of the selector pins.

Having described my invention what I claim as new and desire to secure by Letters 40 Patent is:—

1. In a machine for making perforated music sheets, the combination with a drum over which a perforated pattern sheet is passed, which is to control the operation of 45 punches, of means for feeding the pattern sheet step by step, each of the same length, means for feeding the sheet in which the

perforations are to be made step by step, each of the same length, which steps of movement of the second sheet are to be a 50 predetermined and uniform multiple of the steps of the pattern sheet, whereby the sheet in which the perforations are made remains at rest while the pattern sheet is moved the number of its steps of movement corresponding to one step of the sheet which is being perforated, punches above the sheet being perforated, means for operating the punches at the proper time, punch selector means and means for controlling the selector 55 means from the pattern sheet passing over its drum, substantially as set forth.

2. In a machine for making perforated music sheets, the combination with two drums, for moving sheets to be passed over them, which drums engage said sheets, of a selector mechanism controlled from the sheet on one drum, a punch mechanism controlled by said selector mechanism and serving for making perforations on the sheet 70 passed over the other drum, means for moving each drum step by step, the steps of the drum over which the sheet being perforated is passed being greater than the steps of the drum over which the pattern sheet is 75 passed and means for making one step of the drum over which the sheet being perforated is passed, during a fixed and determinate number of steps, greater than one, of the drum over which the pattern sheet 80 is passed, whereby the drum over which the sheet being perforated is passed remains at rest during the time that the drum over which the pattern sheet is passed makes the predetermined number of steps, substantially as set forth.

Signed at New York city, in the county of New York and State of New York this 20th day of July, A. D. 1914.
